UNITED STATES PATENT OFFICE

LUDWIG REICHOLD, OF WINSTED, CONNECTICUT, ASSIGNOR TO THE FITZGERALD MANUFACTURING COMPANY, OF WINSTED, CONNECTICUT, A CORPORATION OF CONNECTICUT

THERMOSTATIC ELECTRIC SWITCH

Application filed June 27, 1931. Serial No. 547,364.

This invention relates to improvements in thermostatic electric switches, and more particularly concerns a switch and adjusting device therefor which is adapted for employment in obtaining a remote control of the thermostatic switch.

It has heretofore been proposed to provide distant control devices for thermostatic switches, but when such switches are employed with flexible devices such as electric heating pads and the like, the provision of a proper remote control for adjusting the point of cut off of the thermostatic device offers difficulties of construction owing to the bulk and the lack of flexibility in the connecting means.

According to the present invention a thermostatic switch is provided with a controlling portion which may be located remotely from the switch proper whereby the switch may be inserted within a heating pad, for example, while the remote control may be secured at the edge of the pad and project therefrom for easy operation.

One form of construction of the device according to the present invention is set forth on the accompanying drawings, in which:

Figure 1 is a perspective of the switch casing and the remote control structure with connecting elements, and showing diagrammatically certain associated features of the heating system.

Figure 2 is a longitudinal sectional view substantially on line 2-2 of Figure 3.

Figure 3 is a plan view of the device shown in Figure 2, with the upper casing portions removed for exposition of the interiors.

Figure 4 is a detailed sectional view corresponding to Figure 2, but showing the parts in a different operative position.

In these drawings, a thermostatic switch casing comprises the bottom wall 10 and an end wall 11 to which is connected a lid 12 having overlapping side flanges 13 for engagement with the side flanges 14 of the bottom member 10, this relationship being assured by the engagement of depressions 15 in these members, for example. The remote control devices comprises a bottom piece 16 and a top piece 17 which may be molded individually of

insulating materials, such as bakelite, and the pieces held together by a screw 18. Between the two elements is provided a cavity 19 forming an extension of apertures in both pieces 16 and 17. In these apertures is rotatably seated the manually adjustable control piece 20 which likewise may be of insulating material. This piece 20 has an annular flange 21 received within the annular space 19 to prevent withdrawal of the piece 20 from the remote control casing. A radially extending pin 22 on the piece 20 engages the ends (Figure 3) of a driving chain 23. It is preferred to provide a resilient friction washer 23a between one portion of the casing and the flange 21 to prevent looseness of the piece 20.

A resiliently flexible connector 24, of spring steel for example, is connected by rivets 25 to the bottom 10 of the switch casing at one end, and is received at its other end between the portions 16, 17 of the remote control casing, being held in position by cut-away portions in this casing structure and by the screw 18. A contact terminal 26 is secured to this spring piece.

The chain 23 passes through channels 27 formed in the insulating members 16, 17 and then through coil springs 28 which are tightly fitted and clamped between the members 16, 17 and are engaged in nipples 29 formed in the end wall 11 (Figures 2 and 3). Supporting and guiding clamps 24a are provided on the blade 24 to hold the coils 28 in parallel relationship to the blade 24. Within the switch casing, and extending across the central axial plane of the casing, is a stirrup 30 which is secured to the bottom plate 10 and has a threaded opening to receive the externally threaded sleeve 31. This sleeve 31 has fixedly connected thereto a pair of dished plates 32, 33 which together constitute a drum for the reception of the chain 23, which is secured to the drum by a pin 34. Within the sleeve 31 is threadedly mounted a contact member 35. The bimetallic spring blade 40 extends through the rear end of the switch casing and constitutes a second electrical connecting terminal. Within the casing it is supported by insulating members 41 and the

bolts 42 which are maintained insulated from it and from the casing. For greater security a sheet 43 of insulating material such as mica is located above the blade to prevent contact 5 between it and the drum formed of the members 32, 33. On top of this sheet (Figure 2) 10 43 is secured a camming piece 45 which is engaged by a downwardly projecting portion 33a of the plate 33 (Figure 4) whereby the bimetallic blade 40 is pushed away from the contact screw 35, whereby to open the circuit, when the drum comprising the plates 32, 33 has been moved to the proper position, corresponding to the indication of the pointer 20a 15 of the manual control member 20 opposite the indicia "off" (Figure 1). The inner end 44 of the bimetallic blade may engage with the lower end of the terminal screw 35 in Figure 2.

20 As shown in Figure 1 the current supply conductors 50 lead on the one hand to the electrical connecting terminals 40, and on the other hand through the heating resistors 51, 52 and an auxiliary thermostat 53 to the electric connecting terminal 26. It is preferred to provide a condenser 54 in shunt of the heating elements to prevent deterioration of the contact members.

In operation, the device is located with the 30 switch casing inside of a heating pad P (Figure 1), and with the manual control member 20 and adjacent portions of the casing projecting therefrom apertures 17a are provided in the parts of the casing so that the edge 35 binding of the pad may be stitched in position; the current flows through the conductors, the resistor coils 51, 52 to the terminal 26 and thence to the casing 10 and by bridge 30 to the sleeve 31 and contact screw 35. If 40 the device is cold, the bimetallic blade 40 is in its upper position, and its end 44 is engaged with the contact screw 35 so that the current flows through the blade to the terminal end 40 and thence back to the power line. The 45 resistor coils 51, 52 become heated and ultimately the bimetallic blade is caused to arch or bow downward into a position in which it is free of the contact screw 35. The circuit 50 is now open, and the resistor coils 51, 52 de- energized so that the pad will cool slightly.

At a predetermined temperature, contacts 35, 44 close and the heating begins again. This operation continues and the pad is maintained at a temperature determined by the position 55 of the contact screw 35 and the sleeve 31.

It will be noted that the manual control member 20 extends to both sides of its casing 16, 17, and hence it may be grasped between two fingers and rotated about its axis. By 60 this movement the chain 23 is caused to travel and therewith the drum 32, 33 to be rotated, and thus the sleeve to be moved closer to or farther from the position of the blade terminal 44. In this way the temperature of 65 the cut-off may be regulated, and the heating

pad maintained at a higher or lower temperature as desired. If it is found that the high or low temperature is respectively too low or too high, it is possible by removing the lid 12, when the device is being assembled in the 70 heating pad, to regulate the contact screw 35 to a proper initial setting.

By this construction it is possible to control the temperature cut off by regulation of the manual control member 20 which is located 75 outside of the pad, and also to positively open the circuit by moving the member to the "off" position.

The auxiliary thermostat 53 is provided for safety, and is usually set at a slightly 80 higher temperature than the maximum temperature provided in the controllable thermostat, so that it will open and prevent burning out of the resistors 51, 52 in case the bimetallic blade 40 should have its contact piece 44 85 "frozen" to the contact screw 35, or other mechanical injury have occurred. The condenser 54 is provided to decrease the spark at the opening and closing of the thermostat contacts.

It will be noted that the upper surface of the manually operable piece 20 is provided with a triangular portion 20a which serves both to assist in a proper gripping of the device for rotation and as an indicator in conjunction with the legends on the adjacent portion of the upper piece 17 of the remote control casing.

Owing to the flexible nature of the spring 95 blade 24 and of the coils 28, it will be noted that the pad may yield freely and be caused to conform to practically any spatial curvature.

It is obvious that the invention is not limited to the form of construction shown, but 100 that it may be modified in many ways within the scope of the appended claims.

Having thus described the invention, what I claim as new and desire to secure by Letters 110 Patent, is:—

1. A thermostatic electric switch comprising a thermostatically actuated movable contact and a cooperating contact, means for moving said relatively fixed contact toward and from said movable contact, an adjusting device located remote from said contacts, a flexible connection between said means and said device for operating said means, and flexible mechanical connecting means associating said contacts and said device.

2. A thermostatic electric switch comprising a thermostatically actuated movable contact and a cooperating contact, means for regulating the relative positions of said contacts to control the temperature at which the contacts close and open, a control block and a flexible mechanical link connecting the same to said contacts, a regulating piece mounted on said block, and a driving connection

guidedly held to said link between said piece and said means for operating the latter.

3. A thermostatic electric switch comprising a switch casing adapted to be inserted in a heating pad or like structure, a thermostatically actuated and a cooperating contact in said casing, means to adjust said contacts relative to one another, a control casing adapted to be fixed to the pad and project in part therefrom, a flexible link connecting said switch and control casings, a regulating piece in said control casing, and a driving connection guidedly held to said link between said piece and said means.

15 4. A thermostatic electric switch comprising a switch casing, a thermostatically actuated contact in said casing, a cooperating contact having a screw-threaded mounting in said casing, a control casing, a manually rotatable control piece in said control casing, a flexible link for mechanically connecting said casing, a driving chain for connecting said piece and said fixed contact whereby to rotate the latter in its mounting and thereby 20 adjust the same relative to said actuated contact, and means connected to said link for guidedly holding said driving chain.

5. A thermostatic electric switch comprising a switch casing, a thermostatically actuated contact in said casing, a cooperating contact, revolute means for adjusting the contacts with respect to one another, a control casing, a flexible link for connecting said casings, a manually rotatable piece in said 35 control casing, an endless chain for connecting said piece and said means for simultaneous movement, and tubular flexible guards surrounding portions of said chain external to said casings and connected to said link.

40 6. A switch as in claim 5, in which the guards are helical springs, and said link has portions for holding said springs.

7. A switch as in claim 5, in which the guards are helical springs having their ends 45 engaged in said casings, and means are provided on said link for embracing and holding said springs to said link.

8. A thermostatic electric switch comprising a switch casing, a thermostatically actuated contact in said casing, a cooperating contact in said casing, means for adjusting the relative position of said contacts including a screw-threaded member, a drum on said member, a control casing, a revolute regulating piece in said control casing, a flexible link for connecting said casings, and a driving chain connected to both said piece and said means for causing simultaneous movement thereof and guidedly held by said link.

30 9. A thermostatic electric switch comprising a switch casing, a thermostatically actuated contact in said casing, a cooperating contact, revolute means for adjusting the contacts with respect to one another, a control casing, a manually rotatable control piece in

said control casing, a driving chain for connecting said piece and said revolute means whereby to rotate the latter and thereby adjust the contacts with respect to one another, and a device carried by said revolute means 70 for positively disengaging said contacts from one another at one position of said piece and revolute means.

10. A thermostatic electric switch comprising a switch casing, a thermostatically actuated contact in said casing, a cooperating contact having a screw thread mounted in said casing, a drum connected to said cooperating contact, a control casing, a manually rotatable control piece in said control casing, means on said drum and insulated from said thermostatically actuated contact for positively moving said thermostatically actuated contact out of engagement with said cooperating contact in one position of said drum, and a driving chain for connecting said piece and said drum whereby to rotate the latter and therewith adjust said cooperating contact with respect to said actuated contact and also to engage said means with said actuated contact in one position of said parts whereby to positively open the circuit through the switch.

In testimony whereof I affix my signature.
